UNITED STATES PATENT OFFICE.

WILLIAM EDWARD LAMBDEN, OF BROOKLYN, NEW YORK.

DISPLAY-RACK.

SPECIFICATION forming part of Letters Patent No. 723,885, dated March 31, 1903.

Application filed January 2, 1902. Serial No. 88,200. (No model.)

To all whom it may concern:

Be it known that I, WILLIAM EDWARD LAMBDEN, a citizen of the United States, residing at Brooklyn, in the county of Kings 5 and State of New York, have invented a new and useful Display-Rack, of which the following is a specification.

This invention relates generally to display-racks, and more particularly to one adapted 10 for use in connection with a sample or display box; and the invention is particularly adapted for displaying velvets, pluses, and similar fabrics.

The object of the invention is to provide a 15 cheap and simple device which can be applied to the ordinary boxes now in common use and by means of which plush, velvet, or other fabric can be displayed to its best advantage.

20 The invention consists also in certain details of construction and novelties of combination, all of which will be fully described hereinafter and pointed out in the claims.

In the drawings forming part of this specification, Figure 1 is a perspective view showing the practical application of my invention, the rack being set up and the fabric being placed thereon for displaying purposes. Fig. 2 is a perspective view illustrating the rack 25 set up, the fabric being omitted from the rollers and the rack in order to more clearly illustrate the construction of the device. Fig. 3 is a detail perspective view illustrating the manner of journaling the rollers and securing 30 the upright standards. Fig. 4 is an enlarged sectional view showing the journal-plates in section. Fig. 5 is a sectional view illustrating the socket-plates and standards in section. Fig. 6 is a detail sectional view 35 illustrating the manner of connecting the cross-bars to the standards. Fig. 7 is a similar section taken horizontally through the standards and guides, and Fig. 8 is a detail perspective view illustrating a portion of one 40 of the standards.

In carrying out my invention I employ a box or case A, which is constructed substantially the same as boxes or cases now in common use, said boxes having hinged sides A', 50 which turn down in order to more permanently display the goods contained therein.

I prefer to arrange the goods upon rollers B, said rollers being arranged longitudinally within the box, their ends being provided with trunnions B', which rest within the journal-plates C, said plates being secured by screws, rivets, or otherwise to the inner faces of the box ends and provided with slots C', in which the trunnions B' rest, said slots being preferably angular in shape or otherwise 55 designated as "bayonet-slots." Midway between the bearing-plates is arranged a socket-plate D, each end of the box having a socket-plate attached thereto and having a vertical socket D', in which fits the lower end 60 of the upright standard E, said lower end having a flattened portion E', against which the set-screw E² is adapted to bind, thereby holding the standard in a fixed upright position. Inasmuch as there is a socket-plate 65 attached to each end there will of course be two uprights E, and these uprights are connected at their upper ends by means of a cross-bar F and intermediate their ends by means of cross-bar G, said cross-bars F and 70 G having guides F' and G', respectively, which slide upon standards E, and working through these guides F' and G' are the set-screws F² and G², respectively, said set-screws 75 or binding-screws bearing against the flattened portions F³ and G³, respectively, produced upon the outer sides of the standards E, thereby securely locking the cross-bars F and G in their proper horizontal positions. The rack as now set up is ready to display 80 the fabric which is contained within the box and is rolled upon rollers B, and in order to display said fabrics the end portion thereof is unwound from the roller and thrown over one of the cross-bars. The fabric of the other 85 roller is partly unwound and spread across the other cross-bar, as most clearly illustrated in Fig. 1.

It will thus be seen that I provide an exceedingly cheap and simple display-rack, 90 which can be quickly and easily set up and taken down and one which is particularly adapted for use in connection with a merchandise-box.

If desired, the standards and cross-rods can 95 be made of such length that they can be contained within the box at the same time the

goods are arranged therein, so that with each box of goods a rack can be shipped at the same time, if so desired.

Having thus fully described my invention, 5 what I claim as new, and desire to secure by Letters Patent, is—

1. A display-rack consisting of a suitable base, uprights and adjustable cross-bars arranged thereon and parallel rollers revolvably 10 mounted in the base and at a distance below the lowermost cross-bar.

2. A display-rack consisting of a suitable base having slightly-elevated end portions, parallel rollers revolvably mounted therein, standards secured to the ends of the base midway the rollers and adjustable cross-bars connecting the standards.

3. In a display-rack, the combination with a suitable base, of detachable parallel rollers

mounted on said base, adjustable standards 20 secured to the ends of the base intermediate the rollers, and cross-bars connecting and slidably secured to said standards.

4. A display-rack consisting of a box having sockets secured to the inner face of its 25 opposite sides, bearing-plates secured also to said opposite sides, said bearing-plates being arranged upon opposite sides of the sockets and having angular slots produced therein, uprights fixed in the sockets, rollers having 30 trunnions journaled in slotted bearing-plates and cross-bars connecting the uprights as specified.

WILLIAM EDWARD LAMBDEN.
